ASSIGNOR TO GARRETT O. WRIGHT, OF ADRIAN, MICHIGAN.

RAZOR-STROPPING MACHINE.

1,074,095.

Specification of Letters Patent. Patented Sept. 23, 1913.

Application filed April 20, 1912, Serial No. 692,177. Renewed April 23, 1913. Serial No. 763,182.

To all whom it may concern:

Be it known that we, EDWARD B. GIBFORD and WILLIAM P. WELCH, citizens of the United States, residing at Adrian, in the county of Lenawee, State of Michigan, have invented certain new and useful Improvements in Razor-Stropping Machines; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to machines for stropping razor blades, especially designed for stropping the blades of safety razors, and consists in the construction and arrangement of parts hereinafter more fully set forth and pointed out particularly in the claims.

The object of the invention is to provide simple and efficient means for stropping safety razor blades, wherein provision is made for automatically turning the blade holder from side to side so as to successively carry the edge of the blade into contact with the surface of the strop, as the parts carrying the blade are reciprocated upon the strop.

The invention contemplates such an arrangement of parts as will enable the blade to be urged with considerable pressure against the face of the strop during the longitudinal movement of the frame and blade holder thereon, and further contemplates the mounting of the blade holder and frame upon a looped strop having two abrasive surfaces, into action with either one of which the blade may be brought by sliding the frame around the loop of the strop.

The above object is attained by the apparatus illustrated in the accompanying drawings, in which:—

Figure 1 is a perspective view of a stropping device embodying our invention, in operative position upon a strop, the ends of the strop being broken away. Fig. 2 is a section through the device longitudinally of the strop showing the position of the blade holder when the frame is being moved upon the strop toward the right. Fig. 3 is a similar view showing the position of parts when the frame is being moved

upon the strop toward the left. Fig. 4 is a section similar to Figs. 2 and 3 showing the blade holder in the act of swinging. Fig. 5 is a plan view of the reciprocatory frame detached from the main frame upon which it is adapted to be mounted. Fig. 6 is a plan view of the main frame and the reciprocatory frame mounted thereon, with the blade holder omitted and the connecting rods of the reciprocatory frame broken away. Fig. 7 is an enlarged fragmentary view in section, as on line 7 of Fig. 1. Fig. 8 is a perspective view showing the looped strop and the stropper mounted thereon, a portion of the strop being broken away. Fig. 9 is an edge elevation of the strop showing the manner of passing the stropper around the loop from one side to the other of the strop. Fig. 10 is a fragmentary view in plan illustrating the two abrasive surfaces of the strop.

Referring to the drawings, by the characters of reference marked thereon, 1 designates the main frame, which is formed of stamped metal and comprises the flanged side members 2 connected by the transverse end portions 3. Struck out of the central portion of the main frame is a rectangular spring frame, comprising parallel side bars 4 connected by end pieces 5, said end pieces being in turn attached to the sides of the main frame.

The razor strop 6 is a double or looped strop, and is of fabric, preferably webbing, to render it flexible, the surface thereof being treated to give the desired abrasive effect, said strop being adapted to lie between the flanges 2 of the main frame and in practice is threaded so as to pass under the bars 4 and lie upon the end portions 3 of the main frame, as clearly shown in Figs. 2, 3 and 4, said bars 4 being slightly curved or rounded, so as to facilitate the threading of the strop through the frame. The spring of the bars 4 is sufficient to exert the necessary tension upon the strop 6 to afford the required resistance to the movement of the main frame upon the strop, but will allow said frame to slide upon the strop when sufficient pressure is exerted to overcome said friction. The blade holder 7 comprising closed spring jaws between which the blade 8 is adapted to be held, is fixed to a shaft 9 which extends between and is journaled in the side flanges 2 of the main

frame. Also fixed to the shaft 9 at each end thereof is a rocking head 10. These heads are adapted to turn with the shaft 9, and are each provided in the opposite sides 5 thereof with the camways 11. Formed in the side flanges 2 of the main frame are the longitudinal slots 12.

Mounted to reciprocate upon the main frame is a sliding frame comprising the 10 end portions 13 connected by a transverse strip 14. The end portions 13 of the sliding frame are adapted to embrace the side flanges 2 of the main frame, and the strip 14 to lie under the strop, as shown in Figs. 15 2, 3 and 4. To attach the sliding frame to the main frame, transverse rods 15 are employed which are secured at their ends in the ends 13 of the sliding frame, and which pass through the slots 12 in the main frame. 20 The space between the rods 15 is equal to the distance between the outer ends of the cam-ways 11 in the rocking heads 10, and the parts are so disposed that one of said rods is at all times in engagement in one of 25 said ways. It will be noted that the line of the slots 12 is below the pivotal point of the shaft 9 of the blade holder. By reciprocating the sliding frame upon the main frame, the rods 15 will successively enter into and 30 pass from the cam-ways 11 in the rocking heads, imparting to said heads a rocking movement in opposite directions, thereby swinging the blade holder from side to side. With the parts in the position shown in Fig. 35 2, the initial movement of the sliding frame toward the left will cause the rod 15, which is lying in the lower cam-way in the head 10, to swing said head to the right, thereby turning the shaft 9 in the same direction 40 and swinging the blade holder toward the right. As the first rod in this operation passes from engagement with the slot of the lower side of the head, said head will have assumed such a position as to allow the second rod to enter the slot on the opposite side, whereby the swinging movement of the head to the right is continued to the limit of the movement of the sliding frame, 45 said parts being arrested only when the position shown in Fig. 3 is reached, in which 50 position it will be noted that the rod 15 which is in engagement in the slot 11 in the rocking head bears forcibly against the terminal portion of the slot, so as to constantly urge the blade 8 into contact with the strop. By continuing the pressure upon 55 the sliding frame in the same direction, after the parts shall have reached the position shown in Fig. 3, it will cause the main 60 frame to slide longitudinally of the strop and will drag the edge of the blade over the face thereof to effect the required abrasive action upon the blade, as will be well understood. Upon reaching the limit of the 65 movement toward the left, pressure is ex-

erted upon the sliding frame to slide it to the right, causing the rod 15 which engages in the lower cam-way of the rocking head to swing said head toward the left, as illustrated in Fig. 4, the parts being so disposed, that, as the first rod passes from one of the cam-ways 11 in the head, the second rod will enter the opposite cam-way, and complete the swinging operation, so as to carry the blade into contact with the strop 75 on the opposite side, as shown in Fig. 2, after which a further pressure upon the sliding frame will cause the main frame to slide, thereby drawing the blade over the face of the strop and in contact therewith. 80

It will now be understood that the initial operation of moving the sliding frame operates to swing the blade holder and that further pressure upon said frame to slide it will slide the main frame longitudinally of 85 the strop, completing the stropping operation, as will be well understood, the blade holder swinging in reciprocal succession from side to side accordingly as the sliding frame is reciprocated and the main 90 frame is caused to slide along the strop by a continued pressure on the sliding frame in the same direction.

The end portions of the sliding frame are curved outwardly as shown at 16, thereby 95 enabling said end portions to be readily grasped between the thumb and finger to facilitate the manipulation of the strop.

It will be noted that the edge of the blade 8 swings into contact with the strop before 100 the forward rod 15 of the sliding frame engages the limit of the slot 12, whereby the pressure necessary to slide the main frame upon the strop is employed to constantly urge the edge of the blade into contact with 105 the surface of the strop with such force as to produce the necessary abrasive action. It will further be noted that the initial movement of the sliding frame operates to swing the blade holder, so that the cutting of the 110 strop, through the failure of the blade to lift therefrom when the direction of movement is changed, is obviated.

To confine the ends of the strop, a folded plate 17 is employed, which embraces said 115 ends and is secured thereto by a transverse screw 18 (see Fig. 8). Swiveled in the plate 17 is an eye 19 adapted to engage a stationary hook for holding the strop during the operation of stropping. By this arrangement, the strop may be turned to present either of its sides uppermost. When mounted on the strop, as shown in Figs. 8 and 9, the frame cannot be removed therefrom except by withdrawing the screw 18. The loop 125 20 of the strop divides it longitudinally. One portion of the strop extending from the loop is provided with a sharpening surface 21, and the other portion of said strop extending from said loop in the opposite di- 130

rection is provided with a finishing surface 22, as illustrated in Fig. 10. The stropper is first operated upon the strop to cause the blade to engage with the sharpening surface 21, after which the stropper is passed around the loop of the strop, as illustrated in Fig. 9, to bring the blade into operation with the finishing surface 22, the swiveled eye 19 enabling the strop to be readily turned 10 over for this purpose.

The character of the blade holding frame is such as to enable a looped strop of the character shown and described to be employed, because of the fact that the only element lying between the parallel surfaces of the strop is the transverse strip 14. This is a matter of considerable importance as it provides for a sharpening and a finishing strop in one, and enables the stropping frame to be readily moved upon the strop, so as to bring either of said surfaces into operative relation with the blade when the stropping frame is reciprocated. The loop 20 enables the strop to be readily held during 25 the operation of stropping.

Having thus fully set forth our invention, what we claim as new and desire to secure by Letters Patent is:—

1. A stropping machine comprising a main frame having parallel sides and a bottom, one of the sides of said frame having a longitudinal slot, a strop lying in said frame between said sides and having frictional engagement with said bottom, a blade holder 30 pivoted between said sides to swing, a rocking head on the shaft of the blade holder having cam-ways therein, a slide mounted to reciprocate on the main frame, and members attached to said slide passing laterally 35 through said slot and engaging in the cam-ways in said rocking head to cause the blade

holder to swing from side to side as said slide is reciprocated.

2. A stropping machine comprising a main frame having flanged sides, said sides being 40 each provided with a longitudinal slot, a blade holder pivoted in the sides of the main frame above said slots, a rocking head on the pivot of the blade holder having cam-ways therein, a sliding frame mounted on 45 the main frame having parallel sides, transverse rods carried by and connecting the sides of the sliding frame, said rods passing through said slots and engaging in the cam-ways of said rocking head, whereby 50 said head is caused to rock to swing the blade holder as said sliding frame is reciprocated.

3. A stropping machine comprising a main frame having parallel sides and a bottom, a 55 spring frame struck from the bottom thereof, a strop threaded through the main frame to pass below said spring frame and lie upon the end portions of said main frame, the sides of the main frame having longitudinal 60 slots, a sliding frame mounted on the main frame to freely reciprocate, a blade holder pivoted to the sides of the main frame, a rocking head on the pivot of the blade holder, and members on the sliding 65 frame extending through said slots and engaging said head to cause the blade holder to swing from side to side as the sliding frame is reciprocated.

In testimony whereof, we sign this specification in the presence of two witnesses.
